SOFA

Francis M. Kelly, Gardner, Mass.

Application May 26, 1955, Serial No. 36,229

Term of patent 7 years

(Cl. D15—11)

FIG.2

Fig. 1 is a front elevational view of a sofa, showing my new design; and

Fig. 2 is a view in end elevation thereof.

The back of the sofa is conventionally plain and the opposite end is the same in appearance as the end shown in Fig. 2.

I claim:

The ornamental design for a sofa, as shown and described.
